United States Patent Office

Des. 217,709
Patented June 2, 1970

217,709

BOTTLE

James C. McKinney and William D. West, Greenville
County, S.C., assignors to Texize Chemicals, Inc., a corporation of Delaware

Filed Nov. 21, 1968, Ser. No. 14,673

Term of patent 14 years

Int. Cl. D9—01

U.S. Cl. D9—63

FIG. 2

FIG.4

FIG5

FIG. 1 is a front elevational view of a bottle showing our new design;

FIG. 2 is a side elevational view, the opposite side being a mirror image of the side shown;

FIG. 3 is a top plan view;

FIG. 4 is a rear elevational view; and

FIG. 5 is a fragmentary sectional view thereof taken vertically through plane 5-5 indicated in FIG. 3.

We claim:

The ornamental design for a bottle, as shown and described.
